UNITED STATES PATENT OFFICE.

HUGO JUNKERS, OF AIX-LA-CHAPELLE, GERMANY.

PROCESS FOR DETERMINING THE HEATING POWER OF COMBUSTIBLES.

No. 832,611.

Specification of Letters Patent.

Patented Oct. 9, 1906.

Application filed August 10, 1904. Serial No. 220,200%.

To all whom it may concern:

Be it known that I, HUGO JUNKERS, professor in the Royal Polytechnicum at Aix-la-Chapelle, Germany, a subject of the King of 5 Prussia, German Emperor, residing at No. 64 Brabantstrasse, Aix-la-Chapelle, in the Kingdom of Prussia, Empire of Germany, have invented certain new and useful Improvements in Processes for Determining the Heating 10 Power of Combustibles; and I do hereby declare the following to be a full, clear, and exact description of the invention, such as will enable others skilled in the art to which it appertains to make and use the same.

15 My present invention relates to a process for determining the heating power of combustibles, and more particularly of gaseous combustibles.

20 The determination of the heating power of gaseous combustibles by means of a calorimeter, as described in my American Patent No. 555,956, is accomplished in accordance 25 with the general equation

$$\text{Heating value} = \frac{\text{Quantity of liquid} \times \text{difference of temperature}}{\text{Quantity of combustible}}$$

or, in another form,

$$\text{Heating value} = \left(\frac{\text{Quantity of liquid}}{\text{Quantity of combustible}} \right) \times \text{Difference of temperature.}$$

30 and a moment's thought will suffice to show that the first factor of the right-hand side of the equation can be fixed at will by the aid of mechanical means to suit the nature of a combustible whose heating power is to be determined. This being so, there is remaining nothing to be ascertained than the difference in the temperatures of the cooling liquid the latter is showing on entering the calorimeter and on leaving the same, so that the complicated process for determining the heating power of a combustible as at present executed is reduced to the reading off of the desired difference of temperature on a differential thermometer, or upon a galvanometer-scale when electrical means are employed, or, again, by the aid of a common thermometer when one of the two temperatures is kept constant, which can be done by keeping either the cooling liquid flowing into the calorimeter constant by employing ice water or by keeping the temperature of the off-flowing cooling liquid constant by lowering or raising the temperature of the cooling liquid before entering the calorimeter, as circumstances 45 may demand. As the last-named method would cause great inconveniences, besides

forming the source of inaccurate results, the experimenter would naturally decide in favor of the cooling liquid showing a constant temperature on entering the calorimeter.

60

Generally speaking, my present invention is most suitable for liquid and gaseous combustibles, but I wish it particularly understood that when in the following explanations the word "combustible" is employed without any 65 nearer designation a gaseous combustible is meant, as the determination of the heating power of gaseous combustibles in accordance with this process is the most important.

In the accompanying drawings, Figure 1 70 shows a complete apparatus for determining the heating power of combustibles according to my invention. Figs. 2 and 3 are elevations of a similar apparatus, showing certain modifications more particularly herein- 75 after referred to. Fig. 4 is a sectional view of the temperature-governor shown in Figs. 2 and 3. Fig. 5 shows a differential thermometer. Fig. 6 is a side view of another device for reading off the difference in the 80 temperatures, and Fig. 7 is an end view of said device having certain of the parts shown in Fig. 6 removed and other parts added thereto. Fig. 8 shows an arrangement of the thermo elements. Fig. 9 is an elevation, 85 and Fig. 10 is a plan view, of a diagrammatical arrangement for reading off the cubical units or the calories having passed through a combustible meter. Fig. 11 is an elevation of a complete plant for indicating and recording the heating power of combustibles accord- 90 ing to the present invention. Fig. 12 is an elevation of the indicating and recording device having a side wall removed to show the working parts thereof. Fig. 13 is an elevation 95 of the indicating and recording device driven by a gas-meter. Fig. 14 is a plan view of a part of the recording-strip.

The object of my present invention is to show how this important and time-saving 100 result—namely, the determination of the heating power of combustibles—may be accomplished without calculations, as the desired result may be directly read off a scale with exceedingly rare exceptions. With this end in view I am employing an apparatus, as shown in Fig. 1, in which the calorimeter 1 is built in accordance with my American Patent No. 555,956, whereas the combustible-meter 2 and the liquid-meter 3 may 105 be of any suitable construction, but of a given capacity. Both meters are here

shown as being coupled by a sprocket-chain 4, running over the sprocket-wheels 5 of the combustible-meter 2 and over the sprocket-wheel 6 of the water-meter 3. The diameters of the sprocket-wheels are to be chosen according to the ratio the volume of the cooling liquid is to bear to the volume of the combustible, so that the rise in the temperature of the cooling liquid is kept within convenient boundaries. By determining the heating power of a very high graded combustible more cooling liquid would naturally have to be taken per cubical unit of the combustible than it would, for instance, be necessary with weak gases. This ratio once fixed determines the constant of the instrument employed and of the division of the scale into calories, which constants, of course, would be different from those where another ratio has been chosen.

It is evident that instead of sprocket-chains and sprocket-wheels any other suitable driving connection—as, for instance, cog-wheels, as shown in Fig. 2—might be employed. As shown in Fig. 1, the combustible is led by the pipe 7 to the inside of the calorimeter 1, where it is ignited to heat the cooling liquid, as described in my American Patent No. 555,956, whereas the cooling liquid is led into the calorimeter by means of the pipe 8 and leaves it by way of the branch 9 and the discharge-pipe 10. The pipe 8 is provided with a thermometer 11 and the top of the calorimeter 1 with another thermometer 12. To make the difference of the temperature the cooling liquid is showing on entering and on leaving the calorimeter visible at a glance, a device is employed consisting of the capsules 13 and 14, containing air or another suitable gas. These capsules are communicating with the interior of a partly or wholly transparent tube 15, containing a quicksilver thread 16, playing upon a scale 17, divided on the one side in degrees of centigrade and on the other side into calories, which scale might, of course, be divided into degrees of Fahrenheit or Réaumur and calories to correspond to such divisions. For the reception of the capsule 13 the pipe 8 is provided with a casing 18, through which the one end of the tube 15 is passing water-tight, whereas the capsule 14 is incased in a similar manner in the branch 9, through which the other end of the tube 15 is passing. As the capsule 13 is thus obliged to assume the temperature of the cooling liquid flowing to the calorimeter and the capsule 14 is likewise compelled to assume the temperature of the heated cooling liquid flowing through the branch 9, the quicksilver thread 16 must vary its position in accordance with the difference of temperature shown by the inflowing and off-flowing cooling liquid or by the thermometers 11 and 12, which difference of the two temperatures then may be employed

for any calculations, or the calories may be read off directly on scale 17.

Fig. 2 shows an apparatus for serving the same purpose as the one shown in Fig. 1. In this apparatus a calorimeter as described in my American Patent No. 555,956 and a heater 19 as described in my American Patent No. 762,910 are employed, but may be of any other suitable construction. For heating the cooling liquid a gas-jet 20 is provided and connected with the temperature-governor 21. (Shown in section on a larger scale in Fig. 4.) The construction of this governor is well-known and clearly shown in Fig. 4. The liquid or a gas contained in the capsule 22 standing under the influence of the cooling liquid is expanding when the temperature of the latter rises, so that through the motion of the membrane 23 and the valve 24, attached thereto, the free area for the passage of the gas to the gas-jet 20 is reduced at 25, for which reason the gas-jet 20 is reduced in size and in consequence thereof the temperature of the cooling liquid lowered. When, however, the temperature is sinking too fast, the volume of the liquid or gas in the capsule 22 will be reduced, thus causing more gas to pass by 25 to the gas-jet 20, increase the size of the latter, and raise the temperature of the cooling liquid accordingly, so that in this manner the temperature of the cooling liquid is kept constant. Instead of employing the described governor any other governor of suitable construction may be employed. Fig. 3 differs from Fig. 2 inasmuch as the capsule 22 of Fig. 2 is not placed in the short branch tube 26, but in the branch 9, leading the water away from the calorimeter, and that here a thermometer 27 is placed on the short branch tube 26. Besides this, the combustible-meter and the liquid-meter (shown in Fig. 2 as being driven by gear-wheels) are shown in Fig. 3 as being driven by sprocket-wheels and a sprocket-chain, as shown in Fig. 1. The gear-wheels shown in Fig. 2 may of course bear any desired ratio to each other to comply with the conditions of each individual trial.

It is obvious that for making the volume of the combustible bear a fixed ratio to the volume of the cooling liquid other than the mechanical means shown here might be employed. Where the combustibles and the cooling liquid are standing under a higher than atmospheric pressure, as it is supposed to be the case when the two meters are arranged as shown in Figs. 1, 2, and 3, then the combustible, as well as the cooling liquid, is set in motion by the energy stored up in them; but in case the cooling liquid is standing under pressure and the combustible is a suction-gas standing under a less than atmospheric pressure then the energy of the cooling liquid might be employed to force the combustible into the calorimeter under a

pressure necessary for combustion. If, on the other hand, the combustible should stand under pressure, but not so the cooling liquid, then the energy of the combustible might be 5 employed to force the cooling liquid into the calorimeter. When, however, neither the combustible nor the cooling liquid is standing under pressure, then it becomes necessary to employ mechanical means—as, for instance, clockwork, a line-shaft, or any other suitable means—from which the calorimeter and water-meter may receive their motion jointly, or each of the meters may be provided with its own motive device capable 15 of running at different speeds to vary the ratio to suit the nature of different combustibles. If both meters are driven by the same motive device, a uniform speed of the latter does not become an absolute necessity, 20 as the ratio fixed by the mode of coupling the meters to the common motive device is remaining the same whether the speed of said motive device be a high or a low one. As, however, none of such devices are the object 25 of my present invention, they are not shown here and may be easily arranged by any skilled mechanic.

The differential thermometers employed for putting my process into practice may be 30 of any suitable construction. Fig. 5 shows a device for reading off the difference of the temperatures shown by the to and off flowing cooling liquid. In this device the thermometers 28 and 29 are placed sidewise of 35 an adjustable scale 30. This scale can be set to have its zero-point coincide with the same point of the thermometer showing the higher temperature as the other thermometer is showing, so that the quicksilver thread 40 of the first thermometer shows at a glance the desired difference of the temperatures under consideration upon the scale 30.

Another device for serving the same purpose is shown in Figs. 6 and 7. Here two 45 flat hollow spirals 31 and 32 are connected with their adjacent ends to the bevel-wheels 33 and 34, respectively, whereas their outer ends are communicating separately with the capsules 35 and 36, containing quicksilver, 50 which capsules are in a similar manner brought in connection with the calorimeter as the capsules 13 and 14 in Fig. 1. Between the two wheels 33 and 34 similar wheels 37 and 38 are arranged and seated upon the 55 same shaft 39, upon which a pointer 40 is seated, whose movements are made visible upon a scale 41, graduated to show the difference in the temperatures in degrees and, if desired, in calories also. The expansion of 60 the quicksilver in the one vessel or the contraction of the quicksilver in the other will, as is well known, influence the spirals 31 and 32 in such a manner as to cause the rotation of the wheels 33 and 34 in the one way or in 65 the other, and thus cause the wheels 37 and

38 to turn accordingly. As the wheel 37 is secured to the shaft 39, the latter must rotate too, which rotation is duly indicated upon the scale 41 by the pointer 40.

The differential thermometers employed 70 may of course be of any other constructions than these shown here—in fact, may be of any reliable type; but preference is given to thermo elements as shown in Fig. 8, whose soldered joints 42 and 43 may be inserted in 75 any suitable manner into the cooling liquid before entering the calorimeter, whereas the soldered joints 44 and 45 may be inserted into the heated liquid on leaving the calorimeter. In doing so an electric current will 80 be started in said thermo elements whose varying tension is made visible by the needle of the voltmeter 46, so that the tension of this electric current is thus giving an exact measure of the difference in the temperatures 85 of the cooling liquid, since the variation in the tension of the current is the natural result of the fluctuations in the temperature of the cooling liquid. The scale of the voltmeter is of course graduated to show the difference 90 in the temperatures of the cooling liquid in degrees of the centigrade, Fahrenheit, or Réaumur scale, as the case may be, and is preferably further provided with a second scale running concentric with the first-named 95 scale and giving the calories corresponding to any difference of the temperatures indicated on the first-named scale, so that any calculations become superfluous, as the heating power of the fuel is given directly in 100 calories.

To meet any possibilities, the scale for indicating the calories on the voltmeter is made exchangeable, so that in case the ratio of the quantity or volume of the combustible 105 to that of the cooling liquid transferred to the calorimeter per unit of time is changed another scale graduated to suit the new ratio may be affixed to the voltmeter. It is evident that removable scales graduated to suit 110 any ratios in which the combustible and the cooling liquid are introduced into the calorimeter may be employed on other differential thermometers than the one employing thermo elements.

The difference of temperature indicated by the differential thermometer may also be made visible to the eye by recording the difference of temperature automatically upon a recording-strip, on which this difference of 120 temperature may be read off later on. According to the purpose for which the determining of the heating power is taking place, the recording-strip may be uniformly advanced by means of clockwork while the trial 125 is lasting, so that it is made possible to ascertain at any time the heating power of the combustible as recorded by the differential thermometer. The uniform advancement of the recording-strip may also be accom- 130

plished by means of a train of wheels driven by the combustible-meter, so that records for each cubical unit of the combustible which passed through the combustible-meter 5 during the trial may be read off the recording-strip. This mode of recording is particularly very important for gas-works, as thereby the progress of manufacture can be controlled very exactly, besides which it is 10 made possible to exactly determine how many cubic feet of gas of a high heating power and how many cubic feet of gas of a low heating power have been produced. It is even possible to arrange an automatic addition device to indicate the number of calories produced by the gas-works or to indicate how many calories, for instance, a gas-engine has been consuming during a given time.

20 In Figs. 9 and 10 is shown a diagrammatical arrangement of a device suitable for reading off the cubical contents or the calories passing through a combustible-meter. In this device, 47 represents a disk seated 25 upon the shaft of the drum of a combustible-meter, whereas 48 indicates an automatic addition device whose spindle 49 is journaled parallel and radial to the surface of said disk 47. The little friction-roller 50 30 may be kept by any suitable means (not shown here) to the surface of said disk and be connected to a differential thermometer by means of the shifting rod 51 in such a manner as to be moved toward or away from the 35 center of the disk 47. For this purpose the device shown in Fig. 6 could be advantageously employed by keying an arm to the shaft 39 and connecting this arm with said shifting rod 51. If, however, the arrangement 40 shown in Figs. 2 and 3 is employed, a suitable single thermometer may be employed. It is evident that when the friction-roller 50 is standing on the center of the disk 47 it does not rotate at all; but the more it 45 approaches the periphery of the disk 47 the more revolutions the friction-roller will make per minute in accordance with the greater number of cubical units of the combustible or calories contained in them passing through 50 said combustible-meter.

Fig. 11 shows a complete plant for indicating and recording the heating power of combustibles. The general arrangement of this plant is similar to that of the apparatus 55 shown in Fig. 1; but instead of showing the differential thermometer employed there the device illustrated in Figs. 6 and 7 is made use of, which device is provided with means for indicating the temperature in degrees and the 60 heating power in calories and is coöperating with a recording-drum 52. This recording-thermometer is shown in Fig. 12 in elevation, having one of its side walls removed. The capsule 35, arranged in the pipe 8, is connected by the tube 53 with the hollow spiral

31, whereas the capsule 36, arranged in the branch 9, is connected by the tube 54 to the hollow spiral 32. As shown in Fig. 12, the pointer 40 carries a writing-stylus 55 and is moved back and forth in the manner explained above, according to the difference of temperature or variation in the heating power of the combustible under consideration. During these movements of the pointer 40 the writing-stylus 55 traces a line 75 56 on a recording-strip 57 of the drum 52, rotated by any suitable clockwork 58, which meshes with the wheel 59, seated on the shaft of said drum. Simultaneously herewith the difference of temperature in degrees and the 80 heating power of the combustible in calories are shown by the pointer 40 on scale 41. The scale 41 and the recording-strip 57 are visible through the window 60.

Fig. 13 shows how the recording-drum 52 85 is driven by a gas-meter 61—for instance, a station gas-meter as employed at gas-works. The gas passing through the gas-meter will rotate the chain-wheel 62, carried on its shaft 63, which in turn transmits its motion to the 90 chain-wheel 64 of the clockwork 58 by means of the chain 65. The motion thus imparted to the clockwork 58 is transmitted to the recording-drum 52 by means of a suitable train of wheels, and thus the speed of the recording-drum is proportioned to that of the gas-meter 61 in such a manner that one revolution of the drum corresponds to a given number of cubical units of gas—say one thousand cubic feet—passing through said gas-meter 100 during the same length of time. By this arrangement it is made possible to see at any time how many cubical units of gas have passed through said gas-meter and the calories represented thereby. It is evident that 105 during the time the recording-drum is driven by the gas-meter 61 the spring and escape-ment must be removed from the clockwork 58 or switched out.

I claim—

1. The process for determining the heating power of combustibles consisting in introducing the combustible and a cooling liquid in a predetermined ratio to each other into a calorimeter, and subsequently measuring the 115 difference in the temperatures the cooling-liquid had on entering the calorimeter and possesses on leaving the same, substantially as described.

2. The process for determining the heating 120 power of combustibles consisting in introducing the combustible and a cooling liquid in a predetermined ratio to each other into a calorimeter by speeding independently of each other the means for measuring and delivering 125 the combustible and the means for measuring and delivering the cooling liquid to maintain the most suitable ratio for the combustible, and subsequently measuring the difference in the temperatures the cooling liquid 130

had on entering the calorimeter and possesses on leaving the same, substantially as described.

3. The process for determining the heating power of combustibles consisting in maintaining a fixed relation between the speed of the means for measuring and delivering combustibles and the speed of the means for measuring and delivering a cooling liquid to make 5 the volume of the combustible and that of the cooling liquid delivered per unit of time into the calorimeter bear a fixed ratio to each other, and subsequently determining the difference in the temperatures the cooling 10 liquid had on entering the calorimeter and 15 possesses on leaving it, substantially as described.

4. The process for determining the heating power of combustibles consisting in introducing 20 into a calorimeter per unit of time a volume of the combustible bearing a fixed ratio to the volume of a cooling liquid introduced 25 into said calorimeter during the same unit of time, and subsequently indicating the difference 30 in the temperatures the cooling liquid had 35 on entering said calorimeter and which it is showing on leaving it in degrees, substantially as described.

5. The process for determining the heating power of combustibles consisting in introducing 30 into a calorimeter per unit of time a volume of the combustible bearing a fixed ratio to the volume of a cooling liquid introduced 35 into said calorimeter during the same unit of time, and subsequently indicating simultaneously 40 with the heating power of the combustible in calories, the difference between the temperature of the cooling liquid on entering and its temperature on leaving the calorimeter, substantially as described.

6. The process for determining the heating power of combustibles consisting in introducing the combustible and a cooling liquid into a calorimeter in such a manner as to have the 45 volume of the combustible and the volume of the cooling liquid delivered per unit of time into said calorimeter bear a fixed ratio to

each other, and then recording the heating power of the combustible in calories upon a recording-strip, substantially as described. 50

7. The process for determining the heating power of combustibles consisting in introducing the combustible and a cooling liquid in a predetermined ratio to each other per unit of time into a calorimeter; and then recording the heating power of the combustible in 55 calories upon a recording-strip driven by a gas - meter measuring industrially - utilized gas, thus advancing said recording-strip proportionally to the speed of the gas - meter 60 and to the gas consumption and indicating by the line traced on said recording-strip the heating power of each cubical unit of gas industrially utilized, substantially as described. 65

8. The process for determining the heating power of combustibles consisting in introducing the combustible and a cooling liquid in a predetermined ratio to each other into a calorimeter, then indicating the difference in the temperature the cooling liquid had on 70 entering the calorimeter and possesses on leaving same in degrees and the heating power of the combustible in calories, and subsequently recording the heating power of the combustible in calories upon a recording-strip, substantially as described. 75

9. The process for determining the heating power of combustibles consisting in introducing the combustible and a cooling liquid in a predetermined ratio to each other per unit 80 of time into a calorimeter, then keeping the temperature of the cooling-liquid flowing into the calorimeter constant, and finally measuring the temperature of the cooling liquid by a common thermometer on leaving 85 said calorimeter, substantially as described.

In testimony whereof I have signed my name to this specification in the presence of two subscribing witnesses.

HUGO JUNKERS.
